UNITED STATES PATENT OFFICE.

AARON WENGER, OF BROOKLYN, NEW YORK.

HAT-RETAINING DEVICE AND HEAD-SIZE ADJUSTER.

Application filed December 4, 1923. Serial No. 678,446.

To all whom it may concern:

Be it known that I, AARON WENGER, a citizen of the United States, and a resident of the city of New York, borough of Brooklyn, in the county of Kings and State of New York, have invented a new and Improved Hat-Retaining Device and Head-Size Adjuster, of which the following is a full, clear, and exact description.

10 The present invention has relation to attachments for hats and has particular reference to an attachment for women's hats for the purpose of varying the size of the head receiving opening and constituting a means for retaining the hat in place.

One of the outstanding objects of the present invention resides in the provision of an attachment of the character set forth which will serve to retain the hat in place on the head against casual displacement, the device being especially useful in connection with bobbed hair where the use of hat pins is precluded, and which will further be useful for small head sizes.

25 As a further object the invention contemplates a concealed retaining means which is adapted for arrangement within the head receiving opening of the hat for exerting a tension on the head to hold the hat in place, and which will adapt a hat of a given size to heads of various sizes.

As a still further object the invention contemplates a device of the character set forth which is extremely simple in its construction 35 and mode of use, which is inexpensive to manufacture, which is thoroughly reliable and highly efficient in its purpose, and which may be readily applied to and removed from the hat.

40 With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are 45 expressed.

In the drawings:

Figure 1 is a perspective view of a hat equipped with an attachment constructed in accordance with the invention.

Fig. 2 is a fragmentary horizontal sectional view taken approximately on the line indicated at 2-2 in Fig. 1.

Fig. 3 is a face view of one of the elements of the device.

Fig. 4 is a vertical fragmentary sectional view taken approximately on the line 4-4 of Fig. 2.

Referring to the drawings by characters of reference, the retaining device embodies a strip of resilient material 10, preferably 65 spring steel or the like, which is of an appropriate length and flexibility to be snugly fitted within the head receiving opening of a hat to cover approximately one-fourth of the internal diameter of said opening. The opposite ends of the strip are stamped out to provide a reduced shank 11, the outer free end of which is formed with a spear shaped head or spur 12, the said shank at its juncture with the main body of the strip producing a 75 shoulder 13. The medial portion of the strip 10 is provided with a longitudinal opening or slot 14, the purpose of which will be hereinafter set forth. The strip 10 is arranged within a sector-shaped flexible casing 15 through the ends of which the shanks 11 and spurs 12 project with the shoulders disposed within the case and the major portion of the body of the strip 10 being disposed concentrically within the curved side 85 16 of the casing. An elastic flexible contractile strip of material 17 is secured at its opposite ends as at 18 to the opposite ends of the straight wall 19 of the casing. The front wall is connected by a line of 90 stitching 20 in shirred form throughout its length to the contractile strip 17. Preferably the casing or covering 15 is of a material conforming to the material and color of the hat lining L.

In use, the spurs 12 are inserted in the lining at circumferentially spaced points within the head receiving opening to cause the spring or strip 10 and the curved wall 16 of the covering to coincide with the internal diameter of the head receiving opening. This disposes the contractile strip 17 and the shirred straight wall 19 of the cover in intersecting relation to the head receiving opening. A portion of the lining in the covering indicated at P will extend into the medial slot or opening 14 in the spring or resilient strip 10 which will serve to pre-

vent casual raising or lowering movement of the device with respect to the hat. The contractile strip 17 and the shirred portion 19 will engage with the rear of the head of the 5 wearer to exert a tension thereon to hold the hat in place and will compensate for the application of the hat to heads of various sizes, thus in effect rendering the head size of the hat adjustable.

10 I claim:

1. As a new article of manufacture, a combined hat retaining device and head size adjuster, comprising an arcuate resilient element, anchoring spurs at its opposite extremities adapted to removably secure said element within the head receiving opening of a hat, and a contractile member secured at its opposite ends to said element to dispose the contractile member in intersection relation to the head receiving opening.

2. As a new article of manufacture, a combined hat retaining device and head size adjuster comprising an arcuate resilient strip formed with anchoring spurs at its opposite ends for embedding within the lining of the head receiving opening of the hat, a sector shaped covering through the ends of which the spurs project, and a contractile flexible strip of material arranged within the 25 straight wall of the sector shaped covering and secured thereto at its opposite ends, whereby the straight wall of the covering and the contractile strip intersect the head receiving opening, as and for the purpose 30 specified.

3. As a new article of manufacture, a combined hat retaining device and head size adjuster comprising an arcuate resilient strip formed with anchoring spurs at its opposite 40 ends for embedding within the lining of the head receiving opening of the hat, a sector shaped covering through the ends of which the spurs project, and a contractile flexible strip of material arranged within the 45 straight wall of the sector shaped covering and secured thereto at its opposite ends, whereby the straight wall of the covering

and the contractile strip intersect the head receiving opening, the said straight wall of the covering being stitched to the contractile strip in shirred relation.

4. As a new article of manufacture, a combined hat retaining device and head size adjuster, comprising a sector shaped hollow covering member of flexible material, a bowed strip of spring material arranged within and conforming to the curved wall of the covering member, said strip of spring material having reduced shanks projecting from the ends of the covering member and formed with spear shaped terminal spurs adapted to be anchored in the lining of the head receiving opening of the hat, and a strip of contractile flexible material secured at its opposite ends to the opposite ends of the straight wall of the sector shaped covering member whereby the said straight wall and contractile strip intersects the head receiving opening, as and for the purpose specified.

5. As a new article of manufacture, a combined hat retaining device and head size adjuster, comprising a sector shaped hollow covering member of flexible material, a bowed strip of spring material arranged within and conforming to the curved wall of the covering member, said strip of spring material having reduced shanks projecting from the ends of the covering member and formed with spear shaped terminal spurs adapted to be anchored in the lining of the head receiving opening of the hat, and a strip of contractile flexible material secured at its opposite ends to the opposite ends of the straight wall of the sector shaped covering member whereby the said straight wall and contractile strip intersects the head receiving opening, the said spring member having a medial slot or opening therein into which a portion of the covering member and the lining is adapted to protrude for preventing vertical relative movement of the device with respect to the hat.

AARON WENGER.
